L. W. ROOS

ASH TRAY

Filed April 12, 1926

Inventor:

Ludwig W. Roos,
By *Henry Ott* Atty.

UNITED STATES PATENT OFFICE.

LUDWIG WALTER ROOS, OF BASEL, SWITZERLAND.

ASH TRAY.

Application filed April 12, 1928, Serial No. 101,382, and in Switzerland April 25, 1925.

The present invention relates to an improved ash-tray of the type having a hollow chamber for the reception of water which chamber is accessible through an opening in the cover of the chamber, the cover being so shaped that for instance a cigarette placed on the cover cannot fall out of the ash-tray. The feature of the present invention consists in providing a trough so formed between the part in which the opening in the cover is arranged and the outer edge of the ash-tray that a cigarette cannot be laid thereon. Said trough is in connection with the water space and its outer defining surface is so shaped that a burning cigarette placed crosswise to the trough on this surface only bears on its ends so that after the cigarette has burned it bends in, whereby the ashes fall asunder into the water space.

20 A constructional example of this ash-tray is illustrated on the accompanying drawings, in which:

Fig. 1 is a vertical section and

Fig. 2 is a plan view.

25 The upper part or cover 1 of the ash-tray is loosely mounted on the lower part 2, which forms a water space 3 and is intended for receiving ashes, ends of cigarettes or of cigars, i. e. residues of the smoking articles 30 of any kind in burning or extinguished state. The water space 3 is rendered accessible by the upper opening 4 provided in a cap 12 which is loosely mounted on the cylinder 13. The latter is rigidly connected by means 35 of three equally spaced ribs 14, of triangular cross-section, to the concentric flange 15' of the wall 15 of the upper part 1. The wall 15 is bulged in from its highest part 15' towards the above mentioned concentric flange and 40 forms together with the interior parts 12 and 13 a trough 5 situated intermediate of the outer edge 15' of the ash-tray and the opening 4. The highest part 15', which forms the outer edge of the ash-tray, is of such a 45 width that a cigarette cannot be laid thereon. This trough 5 at its lowermost portion is in connection with the water space 3 by means of segment shaped slots 16. The parts 13 and 15 are integral and are preferably made 50 of sheet iron as well as the lower part 2.

If a burning cigarette A (Fig. 1) is placed radially to the annular trough 5 it is only supported at its ends and is not supported in the part intermediate of its ends and it will bend in for instance owing to a shock or after it has burnt further, whereby the ashes of the

cigarette fall asunder, or the cigarette will collapse. The ashes fall through one of the slots 16 into the water space 3 whilst the downwardly gliding cigarette end is arrested in the lower part of the trough. A falling out of the ash-tray of a burning cigarette placed in the trough 5 is prevented under all circumstances. The upper part of the trough is wide enough to place therein a pipe without any danger of the ashes or glowing tobacco falling out of the ash-tray.

55 The cap 12 is provided at its circumference with three radially arranged inclined apertures 8 adapted to take up the burning end of cigarettes (such as B Fig. 1) the other end of which may be supported by the outer edge 15' of the ash-tray. The apertures 8 are closed at their ends by the cylinder 13 so that the cigarettes inserted in the apertures are extinguished whereby an undesirable generation of smoke is prevented.

60 The cylinder 13 is provided with openings 17 adapted to be brought to register with the apertures 8 of the cap 12 by turning the latter to the required angular extent. The burning end of a cigarette pushed through the registering openings 17 and apertures 8 may be sheared off by turning the cap 12.

65 The opening 4 in the cap 12 is star-shaped and opposite each arm of the star on the upper surface of the cap 12 a radially arranged shallow groove 6 adapted to receive a cigar or a cigarette is provided. This manner of shaping the opening 4 and the arrangement 70 of the grooves 6 renders it possible to obtain on a comparatively small space large areas of the openings through which the ashes and other residues are thrown into the water space as well as large surfaces to lay the 75 cigarettes and the like on.

80 The details of the ash-tray may also be modified without departing from the invention. For instance instead of being cylindrical in plan the ash-tray may be flattened 85 on one side to permit its fixation to a wall, for instance in a vehicle, in which case the trough does not need to extend on the flattened side.

I claim:

85 1. An ash-tray, comprising in combination, a receptacle adapted to contain water, a cover for said receptacle defined by a wall that bulges inwardly between a narrow outer edge and a raised cylindrical center portion, and a cap loosely mounted on said cylindrical portion and provided with a central opening.

90 2. An ash-tray, comprising in combina-

tion, a receptacle adapted to contain water, a cover for said receptacle defined by a wall that bulges inwardly between a narrow outer edge and a raised cylindrical center portion 5 provided with apertures in its shell, and a cap turnably mounted on said cylindrical portion and provided with radially disposed apertures for the insertion of cigarettes registering with the apertures in said shell, where-
10 by a relative turning of the cap against the cylindrical portion causes the cigarette ends to be sheared off.

3. An ash-tray comprising a receptacle, a cover mounted on the upper edge of the latter, a cylindrical member mounted in the cover communicating with the receptacle and having a series of peripheral apertures, a cap rotatably mounted on the cylindrical member, and a series of radially arranged pas-
15 sages in said cap adapted to be brought into register with said apertures, whereby a relative turning of the cap on the cylinder causes the walls of the cylinder and cap to operate
20 as cutters for severing the ends of the ciga-

lettes and the like, inserted in the passages 25 and apertures.

4. An ash tray comprising a receptacle, a dished cover mounted on the upper edge of the receptacle and having a central aperture, a cylinder of smaller diameter than the aperture extending from the latter and terminating in a plane of the upper edge of the receptacle, radial ribs connecting the lower edges of the cylinder and cover thereby forming a series of segmental slots therebetween, 30 a cap rotatably mounted on the cylinder, and a series of radially disposed passages in said cap adapted to register with a series of apertures in the periphery of the cylinder, where-
35 by a relative rotation of the cap on the cylinder causes the walls of the cylinder and cap to operate as cutters for severing the ends of cigarettes, and the like, inserted in the pas-
40 sages and apertures.

In testimony whereof, I have signed my 45
name to this specification.

LUDWIG WALTER ROOS.
